Herzfeld, co-partners doing business as
Stephen Rug Mills, New York, N. Y.**

Application January 11, 1937, Serial No. 67,009

Term of patent 3½ years

To all whom it may concern:

Be it known that I, Moubrey D. Baird, a citizen of the United States, residing at Babylon, L. I., in the county of Suffolk and State of New York, have invented a new, original, and ornamental Design for a Rug, of which the following is a specification; reference being had to the accompanying drawing, forming a part thereof.

The figure is a plan view of a portion of a rug, showing my new design.

The drawing shows approximately three-fourths of a rug, to which the design has been applied, the other quarter being a counterpart of the lower end of the rug as shown.

I claim:

The ornamental design for a rug, as shown and described.

MOUBREY D. BAIRD.
